Patented Apr. 9, 1901.

W. SCHARNWEBER.

INDICATOR AND SEAL LOCK COMBINED.

(Application filed June 18, 1900.)

(No Model.)

THE MORRIS PETERS CO., PHOTO-LITHO., WASHINGTON, D. C.

UNITED STATES PATENT OFFICE.

WILLIAM SCHARNWEBER, OF ST. LOUIS, MISSOURI, ASSIGNOR OF ONE-HALF
TO BEVERLY A. DYER, OF SAME PLACE.

INDICATOR AND SEAL-LOCK COMBINED.

SPECIFICATION forming part of Letters Patent No. 671,636, dated April 9, 1901.

Application filed June 18, 1900. Serial No. 20,708. (No model.)

To all whom it may concern:

Be it known that I, WILLIAM SCHARNWEBER, a citizen of the United States, residing at the city of St. Louis, State of Missouri, have invented a certain new and useful Improvement in Car-Seals, of which the following is a full, clear, and exact description, such as will enable others skilled in the art to which it appertains to make and use the same, reference being had to the accompanying drawings, forming part of this specification, in which—

Figure 1 is an elevational view of my improved indicator and seal-lock combined. Fig. 2 is a sectional view, the near wall of the case being removed. Fig. 3 is a vertical sectional view on line 3 3, Fig. 1. Fig. 4 is a vertical sectional view on line 4 4, Fig. 2. Fig. 5 is an elevational view showing the inner face of the rotary locking-disk. Fig. 6 is a top plan view of a portion of my device, showing the rotary locking-disk in its locking position; and Fig. 7 is a similar view showing the locking-disk in its unlocked position.

This invention relates to a new and useful improvement in an indicator and seal-lock combined, the same being particularly designed for use in railway-car doors and is of that type wherein a plurality of symbol-bearing disks are manipulated at each operation of the lock, whereby the combination of exposed symbols on the disks is different after each operation.

Another object is to provide an additional seal to indicate the road upon which or the person who last operated the lock, said seal forming an effectual lock in itself, it being necessary to mutilate or destroy said seal before the hasp can be operated to open the door.

With these objects in view the invention consists in the construction, arrangement, and combination of the several parts, all as will hereinafter be described and afterward pointed out in the claims.

In the drawings, A indicates the side wall of a car to which my improved seal is attached adjacent the doorway.

B indicates the door, and C the hasp on the door, which co-operates with the staple-lug, hereinafter described, said hasp being held in position by a bolt D, said bolt being preferably arranged upon a chain and provided

with the usual seal-wire slot in its lower end, which may be used, if desired.

E indicates the casing which incloses the apparatus constituting my improved car-seal, 55 said casing being secured by suitable bolts to the side wall of the car, whose squared shanks fit in corresponding openings in the casing, nuts being arranged on the inside, as usual, to prevent the casing from being removed 60 when the door is closed. This casing has projecting from it a staple-lug e, which is provided with the usual bolt-opening, said staple-lug co-operating with the hasp and bolt. A sight-opening e' is arranged in the lower portion of the casing, said sight-opening being protected by a piece of glass or other transparent medium, which is preferably flush with the back face of the casing. Suitable flanges e² project from the back face of the casing to 70 form a circular chamber F.

G indicates the crank-arm, fixed to a shaft whose inner end projects into the circular chamber, said crank-arm being formed with an eye in its outer end, through which the 75 locking-bolt is designed to pass. The hub of this crank-arm and the crank-arm pass through a suitably-shaped slot c in the hasp C, said slot being so arranged that the crank-arm occupies a position when the hasp is introduced thereover different from that occupied by said crank-arm when the seal is locked. As shown in the drawings, the slot is in such relation to the crank-arm that the crank-arm occupies a vertical position in order to be in registration with the slot in the hasp, and when the hasp is introduced thereover the crank-arm is designed to be moved upwardly and around, so that the eye in its end registers with the bolt-opening in the staple lug. The hasp at its lower edge is preferably recessed at c' to co-operate with the staple-lug and provided with an outwardly-extending lip c² for receiving the crank-arm and arresting its outward movement in such 85 position that the eye in the end of the crank-arm is in vertical alinement with the opening in the staple-lug. The inner end of the shaft or spindle of the crank-arm before referred to is preferably squared or made non-circular to receive a disk-plate H, said disk-plate being held in position on said shaft by a 90 100

suitable screw-bolt. A hub is provided on the inner face of this disk-plate in order to properly space the same, while a flange h extends from the periphery of the disk-plate, as shown in Fig. 2. This flange tapers at its ends, as shown, a pocket h' being arranged in the inner wall of the flange, said pocket being designed to occupy a position opposite the sight-opening e' in the casing when the crank-arm 10 occupies a position over the staple-lug.

I indicates disks which are preferably circular in shape, said disks bearing different symbols on their faces, said symbols being shown in the drawings as letters from the alphabet. These disks are arranged loosely in chamber F, being held in said chamber by the rotatable disk-plate H, which is fixed to the crank-shaft, practically supports the small disks I on its flange h , and when the crank-arm is turned to the right or in such position as to register with the slot in the hasp the pocket h' is out of registration with the sight-opening. When the crank-arm is rotated to a position to co-25 operate with the staple-lug, the small disks I roll upon each other and upon the flange h , this disturbance causing the positions of said disks I to be changed, so that when the pocket h' registers with the sight-opening it contains 30 a plurality of disks, in this instance three, which may be seen through the sight-opening, forming what might be termed the "combination of the seal." This combination exhibited through the sight-opening continues 35 so long as the disk-plates remain undisturbed, the weight of the superimposed disks holding the disks opposite the sight-opening against accidental displacement due to jarring of the car. Whenever the disk is rotated, as shown 40 in the drawings, about three-fourths of a revolution to register the crank-arm with the slot in the hasp in order to remove the hasp from coöperation with the staple-lug, the flange h is of course turned so as to pass through the 45 upper portion of the chamber F, in which event the disks formerly occupying the pockets h' are discharged on top of the quantity of disks I in the chamber F, said disks being supported by the flange e^2 of the casing. 50 When the crank-arm turns back into its position over the staple-lug, the disk-plate is carried with it, the tapering edge of the flange h easily entering under the loose disks I, causing said disks to ride up the flange, and when 55 the crank-arm occupies its locked position the pocket h' will be opposite the sight-opening, and two or more disks I will have fallen thereinto and will be exhibited through said sight-opening. It will be obvious that the disks 60 exposed through the sight-opening will be different from those formerly exposed, the disks formerly exposed having been carried up by the disk-plate and discharged on top of the series of disks I, while the exposed disks are 65 practically taken from the bottom line of disks I or those occupying positions in the lowest series.

From the above it will be seen that the crank-arm occupies one position when the door is open, and when the hasp is placed in position 70 and the crank-arm passed therethrough the position of the crank-arm and its attached disk-plate is so changed as to present new symbol-disks to the sight-opening. The bolt is now passed through the crank-arm and the 75 staple-lug, locking said parts together. The symbols exposed through the sight-opening are noted by the person sealing the car, and when the car arrives at its destination these 80 same symbols should be exhibited through the sight-opening; otherwise the evidence of tampering with the car will be apparent. An ordinary seal-wire passed through a slot in the lower end of the bolt is usually sufficient to prevent unauthorized persons from tampering 85 with the hasp; but even were the door opened the symbol-disks would exhibit that fact. I prefer, however, to provide means co-operating with the crank-arm to prevent said crank-arm being rotated or displaced by accident.

J indicates a rotary element, preferably in the form of a disk, mounted on the casing E, said disk having a sight-opening j , through which is designed to be exhibited a small 95 plate or piece of glass or friable material K. This rotary element is provided with a projection J' , which is designed to occupy a position in the path of a crank-arm and prevent said crank-arm from being turned out of its 100 locked position. This projection also carries a perforated lug j' , through the opening in which the locking-bolt is designed to pass, said opening being in vertical alinement with the openings in the crank-arm and the staple-lug. This disk J is provided with a peripheral flange j^2 on its inner face, which flange is 105 cut away opposite the sight-opening j . The inner face of disk J is also provided with an enlargement j^3 , forming walls to hold the breakable plate K in place. Pockets j^4 and j^5 are formed in these walls, the latter of 110 which is preferably inclined for coöoperating with a spring-pressed projection L, extending through the casing E and designed to register with said pockets when the disk J is rotated. 115

A circular flange e^3 is formed on the casing E and designed to fit snugly within the peripheral flange of the disk J. This flange e^3 120 is open at its top in order that the breakable plate K may be introduced into its pocket behind the sight-opening in the disk J. A stop e^4 is arranged in juxtaposition to the disk J, said stop coöperating with a lug j^6 for 125 determining the open position of the disk J, the closed or locked position of said disk being determined by the spring-pressed projection fitting in the pocket j^4 .

In operation, assuming the disk to be turned 130 so that its projection J' extends upwardly, the interruptions in the flanges j^2 and e^3 register and permit the breakable plate K to be introduced into its pocket behind the sight-

opening, said plate being pushed down, so as to be within the inner periphery of the flange e^3 . The hasp having been placed in position and the crank-arm turned to lock said hasp 5 in place, as before described, the disk J is now rotated, so as to bring the projection J' into position over the crank-arm, wherein the opening in the lug j' is in vertical alinement with the openings in the crank-arm and staple-lug for the reception of the locking-bolt. It will be noticed that the breakable plate is now held in position by the flange e^3 and that the yielding projection L has passed therebeyond and is seated in the pocket j^4 behind 15 said disk, thus preventing the backward rotation of the disk J. The breakable plate K thus operates to lock disk J in what I will designate as its "closed" or "locked" position. In order to rotate disk J to release the 20 crank-arm, it will be necessary to break the breakable plate K, so that the disk J may be rotated reversely in the absence of the breakable plate, and in such reverse rotation the yielding projection L rides up the inclined 25 pocket j^5 and over the projection j^3 . When the disk J is thus returned to its open position, another breakable plate may be inserted, the broken particles of the first breakable plate being removed by hand. These breakable 30 plates are preferably in the form of glass and have pasted to their backs pieces of paper indicating the road or the name of the person introducing them. In practice it is designed that different roads have breakable plates 35 with their individual marks or printed matter and that each road will use its own plate when sealing a car. By pasting the paper back of the glass plate the broken particles of glass are not liable to become separated, 40 and their removal is thus rendered comparatively easy. Furthermore, where paper is pasted back of the glass the broken particles are not liable to fly out and injure the persons breaking the glass. It will be obvious 45 that clay, porcelain, thin cast-iron, or other material may be employed in the manufacture of these breakable plates.

Where my improved seal is to be used on fruit-cars, a second slot c^3 may be formed in 50 the hasp for coöperating with the crank-arm, whereby when the hasp is locked in place the door will leave a narrow open space for the purpose of ventilating the car.

Flaps or covers may be provided for the 55 sight-openings e' and j for the purpose of keeping out snow, &c.

I am aware that minor changes in the arrangement, construction, and combination of the several parts of my device can be made 60 and substituted for those herein shown and described without in the least departing from the nature and principle of my invention.

Having thus described my invention, what I claim, and desire to secure by Letters Patent, is—

1. In an indicator and seal-lock combined, the combination with a hasp and staple-lug,

of a crank-arm for locking said hasp in place, a disk-plate, and loose circular disks containing symbols which are exposed to view 70 so that different symbols will be presented at each operation of the crank-arm; substantially as described.

2. In an indicator and seal-lock combined, the combination with a slotted hasp, of a 75 crank-arm passing through the slot in said hasp, a casing provided with a sight-opening, a disk-plate fixed to the crank-arm, and loose circular symbol-disks which are exhibited through the sight-opening; substantially as 80 described.

3. In an indicator and seal-lock combined, the combination with a crank-arm for locking the hasp in position, of a casing in which 85 said crank-arm is mounted, a disk-plate secured to said crank-arm, said disk-plate being provided with a pocketed flange, a sight-opening in the casing designed to register with the pocket in the flange when the disk-plate is in one of its positions, and loose 90 circular symbol-disks which are designed to fall in said pocket to be exposed through said sight-opening; substantially as described.

4. The combination with a slotted hasp, of a 95 crank-arm passing through the slot in said hasp, a casing into which said crank-arm is mounted, said casing being formed with a circular flange, a sight-opening, a disk-plate fitting within said flange and provided with a pocketed flange, and a plurality of circular 100 symbol-disks which occupy said pocket and are exhibited through the sight-opening when the crank-arm is turned to lock the hasp in position; substantially as described.

5. The combination with a hasp, provided 105 with a slot, of a crank-arm passing through the slot in said hasp, a rotary element carrying a breakable plate, and a yielding projection for coöperating with said plate to prevent the movement of said rotary element 110 from its locked position; substantially as described.

6. In an indicator and seal-lock combined, the combination with the hasp provided with a slot, of a crank-arm passing through the 115 slot in said hasp, a rotary element designed to be turned into the path of said hasp to lock the same, a breakable disk carried by said rotary element, and a yielding projection coöperating with said breakable disk; substantially as described.

7. The combination with a hasp, of a crank-arm for locking the same in position, a disk J provided with a projection designed to be turned in the path of said crank-arm, a breakable 125 plate carried by the disk J, and a spring-pressed projection coöperating with said breakable plate; substantially as described.

8. The combination with a crank-arm for locking a hasp in position, of an independent rotatable disk J provided with a peripheral flange, a support for said disk, a circular flange extending from said support, openings in said flanges which are designed to

register with each other, and a pocket in the disk for receiving a breakable plate introduced through the registering openings in said flanges; substantially as described.

5 9. The combination with a crank-arm for locking a hasp in position, of a disk J for locking said crank-arm against movement, said disk being provided with a sight-opening, and a pocket for receiving a breakable 10 plate behind said sight-opening, one wall of said pocket having a recess j^4 , and a spring-pressed projection which is received in said recess j^4 , and which coöperates with said breakable plate; substantially as described.

15 10. In an indicator and seal-lock combined, the combination with a crank-arm designed to lock the hasp in position, of an independent rotatable disk for locking said crank-arm in position, means carried by said rotatable 20 disk for locking the same in position, a casing in which said crank-arm is mounted, said casing being provided with a sight-opening, a plurality of symbol-disks contained in said casing, and means connected to said crank- 25 arm for transposing said disks and exhibiting different symbols through the sight-opening whenever the crank-arm is operated; substantially as described.

11. In an indicator and seal-lock combined, 30 the combination with a crank-arm designed to lock the hasp in position, a casing in which said crank-arm is mounted, said casing be-

ing provided with a sight-opening, a plurality of symbol-disks contained in said casing, means connected to said crank-arm for transposing said disks and exhibiting different symbols through the sight-opening whenever the crank-arm is operated, a rotary element carrying a breakable plate, said rotary element locking the crank-arm against movement, and a yielding projection coöperating with the breakable plate in the rotary element to lock said rotary element in position; substantially as described.

12. The combination with a hasp, of a staple-lug with which said hasp coöperates, a crank-arm for locking said hasp in position, a rotary element for locking said crank-arm in position, a breakable plate carried by said rotary element, means for preventing said rotary element from being rotated when once locked in position until said breakable plate is removed, said rotary element, crank-arm, and staple-lug being formed with openings which register when the parts are locked, and 55 a locking-bolt designed to pass through said openings; substantially as described.

In testimony whereof I hereunto affix my signature, in the presence of two witnesses, this 23d day of May, 1900.

WILLIAM SCHARNWEBER.
